METHOD AND APPARATUS FOR LOADING
FLASH LAMPSWalter J. Geiger and Wilson Davidson, Cleveland
Heights, Ohio, assignors to General Electric
Company, a corporation of New York

Application January 14, 1941, Serial No. 374,372

12 Claims. (Cl. 226—19)

Our invention relates to a method and apparatus for providing bulbs of flash lamps with a rumpled wool-like filling comprising the combustible light-giving element thereof.

The development of the combustible element is a very difficult and exacting operation in that it involves the introduction of an extremely fine filamentary material and the assemblage of a very definitely constituted mass within the confines of a bulb. Present day commercially successful flash lamps of the type referred to are provided, for instance, with either a very fine wire or very narrow strips of foil which are uniformly distributed within the interior thereof and depend upon the very rapid burning of said combustible material in the gaseous combustion-supporting atmosphere also contained therein. The properties of the combustible materials must be such that they can be distributed about the entire interior of the lamp so as to form as complete a mixture with the gaseous element as possible and such that they will retain their position therein until the lamp can be used. The usual practice has been to distribute the combustible materials within the bulb as uniformly as possible and to depend upon the stiffness of said materials and their engagement with the bulb and the other parts of the lamp to hold them in place.

The handling and distributing phases of the filling operation present the greatest difficulty, as the combustible materials are usually of aluminum, magnesium or alloys thereof and have a sectional dimension of the order of .001 inch which causes them to be extremely light in weight, difficult to see, etc. The practicability of all operations, of course, depends upon whether they can be used on a commercial scale in an economical manner.

The difficulty of handling and distributing the combustible materials is still greater when said materials are in the form of short strips or ribbons of foil, as a considerable number, 120 in one instance, of said strips or ribbons make up the combustible element of a single lamp. Strips or ribbons of this type are manufactured according to the method and apparatus disclosed in the United States patent application, Serial No. 353,650, of Rippi and Isaac, which was filed August 22, 1940, and make up a flash lamp disclosed in United States patent application, Serial No. 322,520, of Rippi and Isaac, which was filed March 6, 1940.

One object of our invention is to provide a method and apparatus for developing the combustible element of flash lamps in a manner imparting the desired properties to said element.

Another object of our invention is to provide a

method and apparatus for handling the combustible materials in a satisfactory and ready manner.

Still another object of our invention is to provide a method and apparatus for introducing short lengths of the combustible material into bulbs for flash lamps and to the distribution thereof within the interior of the bulbs.

A still further object of our invention is to provide a method and apparatus for repeatedly developing the combustible elements in a succession of bulbs at a very high rate of speed such that flash lamps can be produced economically on a commercial scale.

15 Still other objects and features of our invention will be apparent from the detailed description which follows of our method as applied to the species of our apparatus shown in the drawings.

In the drawings, Fig. 1 is a vertical section 20 through a mid-portion of apparatus comprising our invention; Fig. 2 is a plan view thereof; Fig. 3 is a perspective view of the upper end of the intake tube on a larger scale; Figs. 4 and 5 are vertical sections through modified bulb-holding 25 heads on a larger scale; Fig. 6 is a side elevation of the control switch and associated apparatus; and Fig. 7 is a vertical section through the fluffing head of the apparatus.

In the instance shown in Figs. 1 and 2 of the 30 drawings, a bulb 10 is in the course of being filled with strips or ribbons 11 of a combustible material. The bulb 10 is held by one of the two duplicate heads 12 (or 12a) mounted on the work surface 13 at the left of the apparatus and is located over the end of an inlet tube 14 of the head 12 which forms the means of conducting the strips or ribbons 11 thereto. A rubber gasket 15 and the body 16 of the head 12 seal the open neck 17 of the bulb 10 from the atmosphere and allows 40 said bulb 10 to be exhausted so that a stream of air capable of carrying the strips 11 into the bulb 10 in the desired manner is caused to emerge from inlet tube 14.

In the present instance, the inlet tube 14 is 45 directly connected to the apparatus 18 for making the strips or ribbons 11 by means of the fitting 19, the tube 20, and nozzle 21; and separate corresponding parts such as the tube 20a and nozzle 21a are provided to connect the inlet tube 14a 50 of the adjacent head 12a thereto. All other apparatus connected to the heads 12 and 12a is also duplicated and normally one or the other of said heads 12 and 12a and the apparatus associated therewith are in operation. At such times the strips 11 are drawn into one of the nozzles 21 or

21a as rapidly as they are formed by the influx of air into said nozzle and are carried to the bulb 10 held by the head 12 or 12a by the movement of air through said nozzle 21 or 21a and the tube 20 or 20a and inlet tube 14 or 14a connecting it to the head 12 or 12a. The multiple construction of the filling apparatus permits the operator of the apparatus, who is stationed beside the left edge thereof, to replace and inspect the bulb 10 filled by one head 12 or 12a while another bulb 10 is being filled on the adjacent head and virtually doubles the productive capacity of the apparatus.

The combustible material fed into the bulbs 10 first appears in the cutting apparatus 18 in the form of a sheet 22 of "full hard" aluminum of foil thickness, i. e., .00085 inch, and does not take strip or ribbon form until it passes over the knife edge 23 and into the path of the knife edges of the rotating cutter 24. The course of operations is such that the sheet 22 is fed between the stationary knife edge 23 and the hold-down bar 25 at a uniform rate directly proportional to the speed of rotation of the feed rolls 26 and 27 and separate strips or ribbons 11 of very definite width are severed therefrom. Each strip 11 is but .0008 inch in width and has a length equal to the width (8 inches) of the sheet 22 regardless of the constant feeding operation and the intermittent shearing operation. The stationary knife edge 23 is mounted on a bed 28 carried by the frame 29 of the cutting apparatus 18, whereas the cutter 24 is journaled at opposite ends in extended portions 30 of the frame 29 and is driven from the pulley 31 through the clutch 32 engaging one of said ends. The pulley 31, in turn, is driven through belt 33 and, preferably an electric motor and speed reducer (not shown), and it drives the upper feed roll 26 through the speed reducer 34, the gears 35, 36, 37, 38 and 39 of the gear train 40 and shaft 41. The pulley 31 and gear 35 are mounted on shafts extending from the speed reducer 34, whereas the gears 36, 37 and 38 are mounted on pins indirectly supported by the frame 29. Intermeshing gears like the gear 42 shown in Fig. 2 are provided on the feed rolls 26 and 27 to cause them to turn at the same peripheral speed.

The operation of the cutting apparatus is continuous, but at regular intervals, following the manufacture of the desired number of strips 11 for a lamp, the production of strips 11 is interrupted for a moment by the inactivity of the sheet feeding means. The periods of operation and rest are established by the number of teeth in different groups on the first gear 35 of the gear train 40 and the spaces between each group respectively and form an automatic means by which definite numbers of said strips 11 can be provided for each bulb 10 as hereinafter described.

At the present moment, the exhausting operation is being applied to the head 12 and considerable suction is being created about the mouth of the nozzle 21 which is located directly below the center portion of the stationary knife edge 23. The suction is sufficiently strong to cause a mid-section of the strips 11 to be drawn into the nozzle 21 almost immediately after they are produced and is believed to carry each strip 11 completely into said nozzle 21 before the succeeding strip 11 is drawn into it. The position of the nozzle 21 is not believed to be critical but it is preferred that it be mounted as near the cutting edges as practicable in order to limit the period of time the strips 11 are subject to drafts of air

and other disturbing influences. A bracket 43 holds the nozzle 21 in place and attaches it to the knife bed 28. At the moment the strips 11 are brought under the influence of the sucking force, they are spread out in a comparatively straight line to substantially their full length and, if viewed under a microscope, may appear to be twisted in one direction and again in another at various points. The strips 11 are obviously in the "full hard" condition of the sheet 22 but are not strained so as to present a uniform or non-uniform curled or wavy appearance such as generally associated with certain hairs, wools and metal wires.

15 It is believed that each strip 11 passes to the head 12 separately through the nozzle 21, the tube 20, the fitting 19 and the inlet tube 14 although the cutting apparatus is operated at a speed producing over one hundred strips, 11, per 20 second. As the strips 11 are in a double up position, they take only little more than half the space they would otherwise require and are more effectively gripped by the air stream passing through the apparatus. The bends in the tube 25 20 are made gradual so as to make the path of travel of the strips 11 as smooth and free flowing as possible, and every effort is made to make the apparatus free of all sharp edges and obstructions which could disturb and possibly catch and hold a strip 11. The open mouth of the nozzle 21 which appears in Fig. 3 is flared out so as to present a comparatively long narrow opening in line with the strips 11 and is rounded off on all edges both inside and outside. The opposite end 30 of said nozzle 21 is tapered inward so as to fit into the conical end of the tube 20 and is rounded off very slightly so that the strips 11 cannot catch thereon. A corresponding connection is made 35 between the opposite end of the tube 20 and the fitting 19 for the same reasons. Tight-fitting rubber tubes 44 surround the adjacent parts at both junctions so as to hold the tube 20 in place and eliminate any possibility of leakage through said junctions. The connection between the fitting 19 and the inlet tube 14 is characterized by the slightly flared opening in said inlet tube 14 and the rounding of the adjacent sections of both the fitting 19 and the tube 14.

40 During the course of travel through the nozzle 21, the tube 20, the fitting 19 and the inlet tube 14, the strips 11 are rumpled somewhat because of their very slight strength and speed of movement, but it is not until they strike the interior of the bulb 10 that the major part of the rumpling takes place. At this latter moment, the strips 11 are very likely tangled with preceding and succeeding strips 11 and form a tangled mass which is distributed about the bulb 10 by the air flow. The movement of the strips 11 is too rapid to permit it to be studied, since the strips 11 almost instantaneously build up from the lower portion of the bulb 10 until they form a very uniform mass filling the entire bulbous portion of said bulb 10. The proportions of the inlet tube 14, tube 20 and the other parts of the apparatus and the rate of flow of the air stream are selected with the object of causing a certain number of strips 11, equal to the desired amount of the combustible material for a lamp, to be rumpled to such a degree that they become distributed as widely as possible throughout the interior of the bulb 10. Observation of the rumpled mass shows that the strips 11 are bent in every conceivable direction 45 in a variety of loops or arcs of different size at

nonuniform intervals and present, in general, a curled appearance.

Both the final rumpling of the strips 11 which occurs when said strips 11 impinge on the curved upper end of the bulb 10, and the distribution of said strips 11 about the interior thereof, are controlled to a certain extent by the position of said tube 14 within said bulb 10 and the curvature and surface conditions thereof. Under the particular conditions presented by the bulb 10 shown, it is preferred that the inlet tube 14 be located exactly on the center axis of said bulb 10, and that the end of said tube 14, which incidentally is rounded off both inside and outside, be spaced $\frac{1}{8}$ inch from the top of said bulb 10. Various other spaced relations can be used successfully, but care must be taken not to have the end of the inlet tube 14 in the neck 17 of the bulb 10 or too far from the end thereof or the strips 11 will not impinge on said end with sufficient force, and a void or dead air space may develop at said end which causes said strips 11 to ball-up and collect therein. As shown in Figs. 1, 4 and 5, the inlet tube or conduit (14, 14' or 14'') extends into the bulb to a point beyond the maximum diameter of the bulb. The bulb 10 is coated on the inside with lacquer which must be sufficiently dry to avoid interference with the movement of the strips 11.

Still another factor responsible for the distribution of the strips 11 within the bulb 10 is the flow of air therein resulting from the diversion of the entering air stream. After the air reverses its direction upon striking the bulb 10, it passes downward, losing velocity gradually until finally as it passes out of said bulb 10 through the restricted space between the inlet tube 14 and the bulb neck it has little effect on the strips 11 and they are trapped therein. The neck of the bulb 10 shown has an interior diameter of .495 inch and the inlet tube 14 has a diameter of .437 inch which leaves a space .029 inch wide completely around the neck 17 for the discharge of the air which flows down around the end of said neck 17 and then up to the pipe 45.

The filling operation is very sensitive to differences and should it become desirable to fill differently shaped bulbs it may be desirable to modify the filling head 12 somewhat along the lines of the modifications shown in Figs. 4 and 5. The filling head 12', in Fig. 4 for instance, is especially adapted to accommodate a short neck bulb 10' of almost the exact shape as bulb 10 and operates in exactly the same manner as the former head 12. The head 12', which is shorter, has a gasket 15' which fills a good portion of the body 16' thereof and has an inlet tube 14' with a particularly shaped portion 46 which restricts the flow of air through the bulb neck 17'.

The filling head 12'' in Fig. 5 is especially adapted to accommodate long neck bulbs 10'' of different shape and size from either bulb 10 or 10' and provides additional means of assisting in the distribution of the strips 11 uniformly about the interior thereof. In this particular case, the bulb 10'' rests on a gasket 15'' within a central opening in a gear 47 which is carried by the body 16'' of the head 12'' and is turned at 60 R. P. M. about a vertical axis by the rotation of said gear 47. The purpose of the rotative movement is to cause the strips 11 to be distributed to all sides of the bulb 10'' in equal numbers regardless of any conditions which may have developed to cause said strips 11 to be thrown to right or left of the inlet tube 14''. Obviously the top of the bulb 10'' is less curved and therefore more sensitive to any off-center condition or variation in the delivery

70 that may have developed. The gear 47 is held in place by a shoulder 48 on the lower face thereof which is located in a recess in the body 16'' of the head 12'' and is actuated by a gear 49 mounted on the shaft 50 which is driven from an adjacent source (not shown) through the belt 51 and pulley 52. A bracket 53 attached to the work surface 13 of the apparatus provides the support for the shaft 50 and gear 49 and a guard 54 covers gear 10 47 and gear 49.

In this latter instance the inlet tube 14'' is also differently constructed and is both farther from the top of the bulb 10'' and dependent on other means for restricting the flow of air therefrom. The inlet tube 14'' extends down through the bottom of the head 12'' to a point where it can be connected directly to the tube 20 and is held in place by screws 55 extending from a sleeve 56 surrounding the lower portion thereof. The sleeve 56 functions as the means of controlling the flow of air from the bulb 10'' and of keeping the rumpled strips 11 therein and as such extends up into the neck 17'' of the bulb 10''. The packing 57 and the gland 58 seal the opening between the inlet tube 14'' and the sleeve 56.

In every instance shown, it is preferred that apparatus like that connected to the body 16 of the head 12 as shown in Figs. 1 and 2 be provided to control the exhausting operation and prevent all foreign solid matter such as a strip 11 from being drawn into the main exhaust system. Such apparatus comprises the pipe 45, trap 59, pipe and pipe fittings 60, trap 61, and the electrically controlled valve 62 and is connected to a main exhaust system capable of producing vacuum equivalent to 550-650 mm. of mercury when the barometric pressure is equivalent to 740 mm. of mercury. The size and surface of the bulb and other conditions within the apparatus control the degree of vacuum required, and it is preferred that the line connecting the source thereof to the control valve 62 include a manometer and a second control valve so that the operator can adjust the vacuum to the desired value. Both traps 59 and 61 are alike and are arranged so that air is drawn through an opening 63 in the side of the cap 64 and passes through the screen 65 before going out the end opening therein. The screen 65 is removable with the cap 64 and is of a suitable fineness to catch all particles of any appreciable size which are drawn through the head 12. The control valve 62, on the other hand, corresponds to a duplicate valve 62a connected to the head 12a which is operated in combination therewith through the manipulation of the switch 66 attached to the cutting apparatus 18. The valves 62 and 62a and switch 66 are so connected to the electric line supplying current to the apparatus that first one then the other of said valves are connected to the line for an interval. These intervals of operation cause the exhaust system to be connected to the respective heads 12 and 12a and are caused to coincide with successive periods of operation of the cutting apparatus 18 during which a definite number of strips 11 corresponding to that required by a bulb are produced. In this manner a succession of bulbs are filled with a definite number of strips 11 by the alternate operation of the heads 12 and 12a. As shown in Figs. 2 and 6, the switch 66 is mounted on the arm 67 extending from the frame 29 of the cutting apparatus 18 and is actuated by the lever 68 pivotally attached to the arm 69 extending therefrom which lever 68 engages the control pin 70 of the switch 66 and the cam 71. The cam 71

is mounted on the constantly rotating shaft 12 of the drive means for the cutting apparatus 18 and is so constructed as to manipulate the lever 68 and through it the control pin 10 during the rest periods of said cutting apparatus. The switch 66 is a totally enclosed, single-pole, double-throw type manufactured by the Micro Switch Company of Freeport, Ill., and is actuated by the engagement of lever 68 with either a "high" or "low" portion of the cam 11. The cam 11, in turn, is mounted on the shaft 12 with the gear 25 and is therefore automatically timed with the periods of operation of the cutting apparatus.

When the bulb 10 on head 12, for instance, has been filled and the apparatus has started to fill a bulb on head 12a, the operator removes the filled bulb 10 from the inactive head 12 and replaces it with a different bulb. The filled bulb 10 is then inspected visually to determine the distribution of the strips 11 whereupon it is either set aside with other properly filled bulbs or is placed over the air jet 13 of the fluffing head 14 (Figs. 2 and 7). On occasion, a bulb may not be properly filled due to the improper distribution of strips 11 on opposite sides thereof and must either be discarded or be treated by the fluffing head 14 to correct this condition. The distribution operation is very critical due principally to the extreme light weight and low strength of the strips 10 and some small foreign particle, such as an irregularity in the top of the bulb 11, or a slight off-center or tilted condition of the bulb 10 during filling may have caused more of the strips 11 to have passed to one portion of the bulb 10 than another. A very small particle, such as a small bubble in the lacquer coating on the inner surface of the bulb 10, is sufficient to disturb the filling operation. In placing the bulbs 10 over the fluffing nozzle 13, the operator subjects the strips 11 to a current of air moving up one side of the bulb 10 and down the other in a whirl which is ordinarily sufficient to disturb any bunching of the strips 11 and to correct any irregularity in the distribution thereof. The air escapes from the bulb 10 by lifting said bulb 10 so that the end of the neck 17 is separated from the collar 15 of the fluffing head 14 which collar 15 holds the nozzle 13 in an upright position on work surface 13. Air at a pressure of about two pounds is used in the fluffing head 14 and a period of use somewhat less than the period of operation of the head 12 or 12a is ordinarily sufficient to correct all improper conditions.

What we claim as new and desire to secure by Letters Patent of the United States is:

1. The method of introducing an extremely fine light weight strip of material into the interior of a bulb so as to develop the combustible element of flash lamps therein which comprises conducting the strip into the bulb in a stream of gaseous material at such a speed as to cause said strip to impinge on the bulb with sufficient force to be bent and rumpled into a uniformly constituted mass and in rotating said bulb to cause the rumpled mass to be uniformly distributed about the interior of the said bulb.

2. The method of introducing extremely fine light weight strips of material into the interior of a bulb so as to develop the combustible element of flash lamps therein which comprises conducting the strips into the bulb in a stream of gaseous material at such a speed as to cause said strips to impinge on the bulb with sufficient force to be bent and rumpled into a tangled fluffy mass, and thereafter subjecting

the mass to a whirling current of air to effect the redistribution of the rumpled strips within the bulb.

3. Apparatus for introducing an extremely fine light weight strip of material into the interior of a bulb so as to develop the combustible element of flash lamps therein comprising an inlet tube adapted to extend through the neck and into the bulbous portion of the bulb, means for supporting the inlet tube and bulb in the desired relation to each other, means for causing a stream of a gaseous material to flow into the bulb through the inlet tube at such a speed as to cause the strip to be carried into said bulb and to impinge thereagainst with sufficient force to be bent and rumpled into a uniformly constituted mass and means for causing a relative movement between the bulb and inlet tube to assist in the distribution of the strip about the interior of the bulb.

4. Apparatus for developing the combustible element of flash lamps in bulbs comprising means for cutting successive series of extremely narrow strips of uniform width from end to end from a thin sheet of a combustible material, means for introducing successive series of strips into bulbs present first at one and then at the other of two different locations comprising an inlet tube adapted to extend through the neck and into the bulbous portion of a bulb at each of said locations, means for supporting each inlet tube and a bulb in the desired relation to each other and for closing off the open neck of the bulbs from the atmosphere, tubes connected to each inlet tube leading to the cutting means, means to effect the exhaustion of air from the bulbs through the necks alternately to cause air and a succession of strips to be drawn into one and then the other of the last mentioned tubes and streams of air to flow into the bulbs through the inlet tube associated therewith at such a speed as to cause the strips to be carried into said bulbs and to impinge thereagainst with sufficient force to be bent and rumpled into a uniformly constituted mass, and means actuated by the cutting means for controlling the exhausting means.

5. Apparatus for providing flash lamp bulbs with fillings of combustible material comprising means for supporting a plurality of bulbs; apparatus for successively slicing fine filamentary strips from a thin sheet of material; means, comprising separate conduits, for transporting the strips in gas streams directly from said slicing apparatus into said bulbs; means for periodically effecting cessation of the slicing of strips; and means, operable in proper time relation with said last-named means, for effecting flow of the gas stream in a different one of said transporting means upon each subsequent resumption of operation of said slicing apparatus.

6. Apparatus for loading a flash lamp bulb having a rounded end and an opening at its opposite end with a multiplicity of separate extremely fine strips of combustible material, comprising a suction head having an annular seat portion adapted to support a bulb for exhaustion, a smooth unobstructed feed conduit terminating at one end in an inlet tube extending into the suction head and terminating at its other end in a pick-up nozzle which is open to the atmosphere, the said inlet tube being so proportioned that it extends into the bulb in said head to a point beyond the maximum diameter of the bulb

but sufficiently short of the rounded end of the bulb to permit free passage of the strips from the tube into the bulb, exhaust means connected to the suction head to exhaust the air from the open end of the bulb around the inlet tube and from the feed conduit, the exhaust means being adjusted to create a suction in the system sufficiently high to cause successive strips to be sucked in by the pick-up nozzle and transported through the feed conduit and inlet tube and to impinge against the said rounded end of the bulb and then to be drawn back toward the open end of the bulb to fill the bulb progressively from its open end to its rounded end with a tangled fluffy mass of the strips, the degree of suction being sufficiently low to prevent balling-up of the strips into a compact mass in the bulb, and means to prevent escape of the strips through the open end of the bulb.

7. Apparatus as set forth in claim 6 wherein the exhaust means produces a degree of vacuum equivalent to about 550-650 mm. of mercury.

8. Apparatus for loading a flash lamp bulb having a rounded end and an opening at its opposite end with a multiplicity of separate extremely fine strips of combustible material, comprising a suction head having an annular seat portion adapted to support a bulb for exhaustion, a smooth unobstructed feed conduit terminating at one end in an inlet tube extending into the suction head and terminating at its other end in a pick-up nozzle which is open to the atmosphere, the said inlet tube being so proportioned that it extends into the bulb in said head to a point beyond the maximum diameter of the bulb but sufficiently short of the rounded end of the bulb to permit free passage of the strips from the tube into the bulb, exhaust means connected to the suction head to exhaust the air from the open end of the bulb around the inlet tube and from the feed conduit, the exhaust means being adjusted to create a suction in the system sufficiently high to cause successive strips to be sucked in by the pick-up nozzle and transported through the feed conduit and inlet tube and to impinge against the said rounded end of the bulb and then to be drawn back toward the open end of the bulb to fill the bulb progressively from its open end to its rounded end with a tangled fluffy mass of the strips, the degree of suction being sufficiently low to prevent balling-up of the strips into a compact mass in the bulb, the clearance between the inlet tube and the open end of the bulb being sufficiently small to prevent the strips from being sucked out of the bulb.

9. Apparatus for loading a flash lamp bulb having a rounded end and an opening at its opposite end with a multiplicity of separate extremely fine strips of combustible material, comprising a suction head having an annular seat portion adapted to support a bulb for exhaustion with its open end lowermost, a smooth unobstructed feed conduit terminating at one end in an inlet tube extending upwardly into the suction head and terminating at its other end in a

pick-up nozzle which is open to the atmosphere, the said inlet tube being so proportioned that it extends into the bulb in said head to a point above the maximum diameter of the bulb but sufficiently short of the rounded end of the bulb to permit free passage of the strips from the tube into the bulb, exhaust means connected to the suction head to exhaust the air from the open end of the bulb around the inlet tube and from the feed conduit, the exhaust means being adjusted to create a suction in the system sufficiently high to cause successive strips to be sucked in by the pick-up nozzle and transported through the feed conduit and inlet tube and to impinge against the said rounded end of the bulb and then to be drawn down toward the open end of the bulb to fill the bulb progressively from its open end to its rounded end with a tangled fluffy mass of the strips, the degree of suction being sufficiently low to prevent balling-up of the strips into a compact mass in the bulb, and means to prevent escape of the strips through the open end of the bulb.

10. The method of loading a flash lamp bulb having a rounded end and an opening at its opposite end with a multiplicity of separate extremely fine strips of combustible material, which comprises applying suction to the open end of the bulb to draw the strips thereinto from a point remote from the bulb, and confining the strips in a passage during their travel from the said point so that they are directed at the rounded end of the bulb and are released from the passage at a point beyond the maximum diameter of the bulb, and regulating the degree of suction to an amount sufficient to cause the strips to impinge against the said rounded end of the bulb and be drawn back toward its open end to fill the bulb progressively from its open end to its opposite end with a tangled fluffy mass of the strips.

11. Apparatus for loading a flash lamp bulb with a filling of combustible material comprising means for supporting the bulb, means for slicing fine strips from a sheet of foil, a conduit having an entrance end so disposed as to receive the strips as they are formed and having its delivery end located in said bulb at a point beyond the maximum diameter thereof, and means for applying suction to the open end of the bulb to draw the strips into the conduit and thence into the bulb.

12. The method of loading a flash lamp bulb with combustible material which comprises slicing a multiplicity of separate extremely fine strips from a sheet of foil at the entrance of a conduit extending into the bulb, applying suction of sufficient force to the open end of the bulb to draw the strips into the conduit and to cause them to be released from the conduit at a point beyond the maximum diameter of the bulb and to be directed toward its rounded end so that it will gradually fill with a tangled fluffy mass of strips.

WALTER J. GEIGER.
WILSON DAVIDSON.
